(Cl. D34—15)

To all whom it may concern:

Be it known that I, Charles Henry Hyman, a citizen of the United States, residing at New York city, in the county of Bronx and State of New York, have invented a new, original, and ornamental Design for a Toy Phonograph, of which the following is a specification, reference being had to the accompanying drawing, forming part thereof.

In the drawing:

Fig. 1 is a side view of a toy phonograph showing my new design;

Fig. 2 is a top plan view.

I claim:

The ornamental design for a toy phonograph, substantially as shown.

CHARLES HENRY HYMAN.
